TELESCOPE SIGHT MOUNTING

Marcus L. Stith, San Antonio, Tex.

Application April 22, 1937, Serial No. 138,304

6 Claims. (Cl. 33—50)

This invention relates to new and useful improvements in telescope sight mountings.

One object of the invention is to provide an improved means for mounting a telescope on a rifle or other gun, whereby the scope may be readily adjusted and also whereby said scope does not interfere with the handling of the gun.

An important object of the invention is to provide an improved mounting for attaching a telescope to a gun barrel and having means for adjusting the telescope laterally of the axis of the barrel, as well as vertically thereof; the adjusting mechanism being rugged and substantially coarse, whereby accurate adjustment of the scope may be effected without the usual ultra fine adjusting devices, which are easily damaged and which require careful and expert operation.

Another object of the invention is to provide an improved mounting of the character described, wherein the telescope is supported on the gun at two points which are spaced a substantial distance apart, with means for obtaining an adjustment of the scope with relation to the gun by swinging the same on one of its supporting points; the distance between the supporting points making for a wide range of adjustment of the scope with relation to the target with a minimum movement of the scope with relation to the gun.

Still another object of the invention is to provide an improved mounting for securing a telescope to a gun barrel which is so constructed that the scope is mounted close to the barrel and is streamlined so that the projection of the scope is minimized, whereby the same does not interfere with the insertion of the gun into its scabbard and also whereby danger of damaging the scope while handling the gun, is obviated.

A further object of the invention is to provide an improved mounting for a telescopic sight of a gun having means for shading the objective lens of the telescope from the sun and for protecting said lens from damage, whereby more accurate shooting is possible.

Still another object of the invention is to provide a mounting of the character described, having means for compensating for temperature changes of the gun barrel due to repeated firing thereof, whereby the telescope is positively maintained in adjusted positions at all times.

A still further object of the invention is to provide improved means for mounting a telescope on a gun, said means being so constructed that it may be attached to any type of gun and also

being flexible to the extent that it may support the telescope either directly above the gun barrel or to one side thereof.

A construction designed to carry out the invention will be hereinafter described, together with other features of the invention.

The invention will be more readily understood from a reading of the following specification and by reference to the accompanying drawing, in which an example of the invention is shown, and wherein:

Figure 1 is a partial elevation of a rifle, having a telescope attached thereto by a mounting, constructed in accordance with the invention.

Figure 2 is a transverse, vertical sectional view, taken on the line 2—2 of Figure 1.

Figure 3 is a longitudinal, sectional view of the objective end of the telescope, showing its mounting to the rifle barrel.

Figure 3a is an isometric view of the compensating member.

Figure 4 is a transverse, vertical, sectional view, taken on the line 4—4 of Figure 3.

Figure 5 is an end elevation of the clamping collar for supporting the inner end of the telescope,

Figure 6 is a side elevation of the same,

Figure 7 is an end elevation of the supporting post or bracket for the clamping collar shown in Figures 5 and 6.

Figure 8 is a side elevation thereof,

Figure 9 is a sectional view of the lateral adjusting micrometer screw which is threaded in the post,

Figure 10 is a view of the set screw for the micrometer screw,

Figure 11 is a transverse, vertical, sectional view, taken on the line 11—11 of Figure 1.

Figure 12 is a view, similar to Figure 3, showing a modified form of mounting the objective end of the telescope,

Figure 13 is a plan view thereof, and

Figure 14 is a transverse, sectional view, taken on the line 14—14 of Figure 12.

In the drawing, the numeral 10 designates a portion of the stock of a rifle, which may be of any suitable construction. The usual rifle barrel 11 has its rear end supported in the stock in the usual manner and the shell chamber 12 is located at the rear of the barrel. The ejecting bolt 13 of the rifle has its outer end slidable in the shell chamber 12 and its rear end has the usual hand lever 14 secured thereto. The bolt is slidable through a receiver or collar 15 which is supported in the stock 10 at a point preferably

above the trigger 10' of the rifle. All of the above parts are of the usual construction and form no part of the present invention. They have been described merely for the sake of clarity.

A telescope 16 of the usual commercial type designed for mounting on guns has the adjustable eye piece 17' at one end of its barrel or tube. An objective lens 17 is located within the tube at the outer end thereof (Figure 3). It is desirable that the telescope 16 be mounted as close to the gun barrel 11 as is possible and also that said telescope be arranged to undergo a lateral adjustment with relation thereto.

For mounting the telescope on the rifle, a sleeve 18 is secured to the rear end of the barrel 11 and overlies the chamber 12. The forward end of this sleeve rests on a saddle 19 which has its upper surface recessed to receive the sleeve, as is clearly shown in Figure 4. The underside of the saddle 19 is flat and rests on a supporting block 20, which block has its underside curved to conform to the surface of the barrel 11. The block 20 is fastened to the barrel 11 by a screw 21. A similar screw 22 extends through the sleeve 18, through the saddle 19 and through the other end of the block 20 and then into the barrel 11. With such arrangement, it will be obvious that the sleeve is rigidly fastened in axial alinement with the barrel 11. The forward or objective end of the telescope 16 is inserted within the sleeve 18 and does not extend entirely therethrough but, as shown in Figure 3, terminates short of the forward end of said sleeve. The internal diameter of the sleeve 18 is made several thousandths of an inch larger than the diameter of the telescope tube, whereby a steel compensating plate or shim 23 may be interposed between the telescope and sleeve. This steel member has its ends normally bent downwardly as shown at 23' in Figure 3a, and acts to hold the outer or objective end of the telescope in positive engagement with in the sleeve 18. Due to the springiness or resiliency of the member, the same prevents any play of the telescope within the sleeve and absorbs shock and vibration. The steel member also compensates for temperature changes of the gun barrel due to repeated firing of the gun in rapid succession and therefore provides for the maintenance of the position of the telescope with relation to the gun barrel 11.

Since the end of the telescope 16 terminates short of the outer end of the sleeve 18, it will be manifest that the sleeve acts as a sunshade to protect the lens 17 of the telescope from the sun rays. Also the extended end of the sleeve protects the lens from accidental damage. It is pointed out that the forward end of the sleeve 18 is inclined rearwardly toward its upper end whereby a streamlining effect is given. This incline at the outer end of the sleeve obviates danger of the sleeve hanging or becoming caught on obstructions while the gun is being handled and also makes for easy insertion of the gun into its scabbard.

From the above, it will be seen that the sleeve 18 positively supports the forward or objective end of the telescope 16 in its proper position on the gun barrel. For adjustably supporting the opposite end of the telescope 16, a clamping collar 24 is provided (Figures 1 and 2). The collar 24 is split and encircles the tube or barrel of the telescope and suitable binding screws 25 are arranged to securely clamp said collar therearound. The clamping collar 24 is supported on

a bracket 26 which is secured by suitable screws 27 to the receiver 15 through which the gun bolt 13 slides, as is clearly shown in Figure 2. The bracket 26 extends upwardly from the stock 10 of the rifle and is disposed contiguous to one side of the clamping collar 24. For fastening the collar 24 to the supporting bracket 26, said bracket has its upper end or portion formed with a threaded opening 28 through which a micrometer screw 29 is threaded. A slot 30 extends from one vertical edge of the bracket 26 inwardly to the opening 29, whereby said opening may be increased or reduced depending upon the closure of the slot 30 (Figure 8). A binding screw 31 is threaded downwardly through the bracket and is adapted to normally hold the opening 28 to a fixed size so that the micrometer screw 29 may be threaded therethrough. Obviously, if the binding screw 31 is tightened with the micrometer screw 29 within the opening 28, said screw 29 will be clamped in a predetermined position and will be incapable of movement until such time as the screw 31 is loosened so as to permit an increase of the opening 28. With the arrangement of the slot 30 and the binding screw 31 it is possible to clamp the micrometer screw 29 in any position within the opening 28. Normally, the inner end of the screw 29 engages the outer surface of the clamping collar 24.

The screw 29 is provided with a bore 29' through which a supporting screw 32 extends. The bore of the screw 29 is countersunk so as to receive the head 32' of the screw 32. The inner end of the screw 32 is arranged to be threaded into an opening 33 provided in the side of the clamping collar 24, whereby said clamping collar is supported on and secured to the bracket 26. Since the inner end of the micrometer screw 29 is engaging the side of the collar 24, an adjustment of the screw 29 with relation to the bracket 26 will cause a variation of the space between the collar 24 and the bracket 26. Therefore, it is possible to change the position of the clamping collar 24 with relation to the axis of the barrel 11 of the rifle. To accomplish the adjustment, it is only necessary to loosen the supporting screw 32 and the binding screw 31 after which the micrometer screw 29 may be adjusted to its proper position. The head of the screw 29 may have suitable indication or marking A (Figure 1) thereon so as to aid in the adjustment. After the screw 29 has been properly adjusted, it is only necessary to tighten the binding screw 31 and the supporting screw 32 and the rear end of the telescope 16 is again secured in a fixed position with relation to the axis of the gun barrel 11. It is of course obvious that the screw 22 which holds the sleeve 18 on the gun barrel 11 must be loosened while the rear end of the telescope 16 is being adjusted, which permits the telescope to swing or pivot laterally on the screw 22 whereby the angle or axis of the telescope is changed with relation to the axis of the gun barrel. After the adjustment of the screw 29 has been completed, the screw 22 passing through the sleeve 18 is again tightened.

It is pointed out that the screw 22 is located a substantial distance from the micrometer screw 29 whereby the fulcrum point on which the telescope swings is a substantial distance from the point of movement of said telescope. This increased radius of swing of the telescope during the adjustment permits a very accurate and quick adjustment of the telescope to a predetermined position without minute micrometer setting and

this is an important feature of the invention. The adjustment may not only be made accurately but very quickly and further the adjusting mechanism is very rugged and not subject to damage 5 during handling of the gun. The mounting is such that the telescope is located right on the gun barrel which minimizes the distance between the gun axis and the telescope axis. The streamlining of the sleeve 18 permits the scope to enter 10 the scabbard of the gun whereby it need not be detached when the gun is not in use. The sleeve also provides an integral sunshade for the objective lens 17 of the telescope, while the steel plate or shim 23 compensates for the temperature 15 changes in the gun barrel due to repeated firing of the gun.

The telescope is shown as mounted in axial alignment with the gun barrel which causes said telescope to overlie the shell chamber 12 and ejecting bolt 13 of the rifle. During firing of the rifle it will be evident that as the bolt 13 is pulled rearwardly the shell is ejected from the chamber 12 and in some rifles is thrown upwardly. In order to prevent the shell from striking the telescope 25 16 and to properly eject said shell a deflector 34 is provided (Figures 1 and 11). The deflector takes the form of a collar which is split so as to be engaged around the barrel or tube of the telescope 16. A suitable set screw 35 securely 30 fastens said deflector in position. The collar has an extension 34' which overlies the bolt 13 and which is inclined as is clearly shown in Figure 11. As the shell is ejected from the chamber 12, it strikes the inclined surface 34' of the deflector 35 and is thrown outwardly to one side of the rifle, whereby said shell is ejected and damage to the telescope is prevented.

Although the telescope is shown as mounted directly above the rifle, it is evident that the 40 same could easily be mounted to either side out of axial alignment with the gun barrel. In such case the block 20 would take the form of a flat bar and would project outwardly to one side of the rifle barrel 11. The sleeve 18 would be secured to such flat bar. In such instance, the 45 clamping collar 24 would be secured to the outer surface instead of to the inner surface of the supporting bracket 26. If it were desired to locate the telescope on the left side (Figure 2) of the rifle barrel, the bracket 26 could be mounted on the opposite side of the collar 15 and gun stock 10.

In many instances, it is desirable to mount the telescope 16 so that it might undergo a vertical adjustment with relation to the gun barrel, as 55 well as a lateral adjustment with relation to the axis thereof. In such instance the mounting of the supporting sleeve 18 at the objective end of the telescope is as shown in Figures 12 to 14. In 60 such case the sleeve is secured by a screw 36 to one end of a base plate 37 which plate extends forwardly of the sleeve 18. The base is provided with a threaded opening 38 and a slot 39 extends from this opening to the outer end of the plate. 65 A binding screw 40 extends transversely in the extreme outer end of said plate and is adapted to control the space of the slot 39. A micrometer screw 41 is threaded in the opening 38 and has its underside resting on the saddle 42 which is 70 secured to the rifle barrel 11 by machine screws 43. The micrometer screw 41 has a bore 41' through which a screw 44 extends.

When it is desired to obtain a vertical adjustment of the telescope by raising the objective end 75 thereof, the rear micrometer screw 29 is loosened

so that the telescope may swing or pivot on the supporting screw 32. The binding screw 40 and the screw 44 are then loosened to permit rotation or adjustment of the micrometer screw 41, and as the latter is rotated the base plate 37 is lowered or raised with relation to the gun barrel 11. When the proper adjustment is had the screw 44 is then tightened and the binding screw 40 is also tightened, whereby the micrometer screw is securely clamped in position, which positively 10 prevents any movement of the base plate 37 which supports the forward end of the telescope. The rear micrometer screw 29 is then properly adjusted for the lateral position of the telescope. With this arrangement, it is obvious 15 that the telescope may be properly adjusted either laterally or vertically of the gun barrel 11. Due to the substantial distance between the adjusting point and the fulcrum point or pivot on which the telescope swings, it is possible to 20 get a very accurate adjustment. The adjusting mechanism is rugged and not subject to damage and may be easily operated by any inexperienced person. The minute micrometer settings usually employed in telescope mountings for rifles are 25 entirely eliminated and a most simple and effective mounting is had.

What I claim and desire to secure by Letters Patent is:

1. A telescope sight mounting for firearms including, an elongate sleeve attached to the barrel of the firearm and adapted to receive the objective end of the telescope, said sleeve having the rear portion thereof engaging the shell chamber of the firearm and the forward portion thereof 35 overlying the barrel, whereby the objective end of the telescope is mounted in close proximity to the barrel, a clamping member surrounding the opposite end of the telescope, an upright bracket on the side of the firearm extending upwardly adjacent the clamping member, a micrometer screw threaded through the bracket and having its inner end abutting the clamping member, and a binding screw passing axially through the micrometer screw and threaded into the member for locking the member tightly against said micrometer screw, the adjustment of the latter spacing the member from the bracket a desired distance, whereby a lateral adjustment of the telescope with relation to the 50 axis of the firearm barrel may be effected.

2. A telescope sight mounting for firearms including, an elongate sleeve for receiving the objective end of the telescope, a relatively thin supporting plate secured to the barrel of the firearm, means for adjustably attaching the sleeve to the plate whereby a vertical adjustment of the sleeve and objective end of the telescope may be effected, a clamping member surrounding the opposite end of the telescope, an upright bracket on the side of the firearm extending upwardly adjacent the clamping member, a micrometer screw threaded through the bracket and having its inner end abutting the clamping member, and a binding screw passing axially through the micrometer 65 screw and threaded into the member for locking the member tightly against said micrometer screw, the adjustment of the latter spacing the member from the bracket a desired distance, whereby a lateral adjustment of the telescope 70 with relation to the axis of the firearm barrel may be effected.

3. A device for mounting telescopes on guns, including a substantially plate-like member fixed to the bottom of the telescope and having a ver- 75

tical threaded opening therein, means to connect the member to the front part of the telescope, a second substantially plate-like member underlying the first member and secured to the upper side of the gun, rotatable means disposed between the members having a part threaded into said opening and having an operating part extending beyond the members whereby to rotate same to effect vertical adjustments of the first member, and thereby the front end of the telescope relative to the gun, means to hold the rotatable member against rotation following adjustment thereof, and means to connect the rear end of the telescope to the gun to provide for said vertical adjustments of the front end thereof.

4. A device for mounting telescopes on guns, in accordance with claim 3, wherein the holding means for the rotatable means consists of a screw

having threaded engagement with the gun, and which has its head concentric with the threaded opening of the first member for manipulation through the opening to be moved to seat against the rotatable means.

5. A device for mounting telescopes on guns, in accordance with claim 3, wherein the holding means for the rotatable means has a part in register with the threaded opening to provide for manipulation thereof through said opening.

6. A device for mounting telescopes on guns, in accordance with claim 3, wherein the rotatable means consists of a substantially disk-like element and wherein the holding means consists of a screw threaded into the gun and having its head impingeable against the disk-like element.

MARCUS L. STITH.
